(57) **CLAIM**

I claim the ornamental design for the food scoop, as shown and described.

DESCRIPTION

FIG. 1 is a perspective view of a food scoop, showing my new design;

FIG. 2 is a right side view of the food scoop, the left side view being a mirror image;

FIG. 3 is a top view of the food scoop;

FIG. 4 is a bottom view of the food scoop;

FIG. 5 is a front view of the food scoop; and,

FIG. 6 is a back view of the food scoop.
